DESIGN FOR A SUNDIAL

Raymond Wesley Anderson, New York, N. Y.

Application November 11, 1936, Serial No. 65,850

Term of patent 7 years

To all whom it may concern:

Be it known that I, Raymond Wesley Anderson, a citizen of the United States, residing at New York, in the county of New York and State of New York, have invented a new, original, and ornamental Design for Sundials, of which the following is a specification, reference being had to the accompanying drawing, forming part thereof.

Fig. 1 is a vertical front view of a sundial, showing my new design; and

Fig. 2 is a vertical side view of the sundial, which consists of an opaque gnomon supported within a transparent globular element, slightly flattened at the top and bottom, on the surface of which is a translucent band graduated in time units.

I claim:

The ornamental design for a sundial, as shown and described.

RAYMOND WESLEY ANDERSON.
